BILLFOLD

John Hughes, Jr., Milwaukee, Wis., assignor to Enger-Kress Company, West Bend, Wis., a corporation of Wisconsin

Application December 3, 1953, Serial No. 27,883

Term of patent 7 years

(Cl. D87—3)

To all whom it may concern:

Be it known that I, John Hughes, Jr., a citizen of the United States, residing at Milwaukee, in the county of Milwaukee and State of Wisconsin, have invented a new, original, and ornamental Design for a Billfold, of which the following is a specification, reference being had to the accompanying drawing forming part thereof.

Fig. 1 is a plan view of a billfold showing my new design, the reverse side being substantially plain;

Fig. 2 is an edge view of the billfold of Fig. 1; and

Fig. 3 is an end view looking at the left hand edge of Fig. 1.

The characteristic features of my design reside in the portions shown by means of full lines in the drawing.

I claim:

The ornamental design for a billfold, substantially as shown and described.
